UNITED STATES PATENT OFFICE.

ARTHUR E. SCHUFFENHAUER, OF SOUTH CHICAGO, ILLINOIS.

APPARATUS FOR CONSTRUCTING ARCHES.

1,076,240.

Specification of Letters Patent.

Patented Oct. 21, 1913.

Application filed March 28, 1913. Serial No. 757,349.

To all whom it may concern:

Be it known that I, ARTHUR E. SCHUFFENHAUER, a citizen of the United States, and a resident of the city of South Chicago, 5 county of Cook, and State of Illinois; have invented certain new and useful Improvements in Apparatus for Constructing Arches, of which the following is a specification.

10 My invention relates to improvements in arch construction.

At the present time great difficulty is experienced in repairing a damaged arched roof, as for instance the arched roof of an 15 open hearth furnace, since, at the present time, the only method which is used in building and repairing roofs of this character, requires the use of a supporting element or center at the under side of the roof in order 20 to support the bricks or units of the arch until the key brick or unit is inserted completing the arch, the arch, after the key brick or unit has been inserted, being as is known, capable of supporting itself. In the 25 case of a furnace of the character mentioned, where the roof becomes damaged during the operation of the former, the repair of the roof by means of the method now used, as above mentioned, is effected with great diffi- 30 culty and danger, the heat within the furnace almost precluding the possibility of arranging a supporting element at the under side of the arch for the support of the units or bricks of the arch such as is necessary 35 until the arch is completed.

It is therefore the object of my invention to provide an apparatus whereby an arch may be readily and easily constructed or whereby a damaged or any arch may be 40 readily and easily repaired, without necessitating the use of means arranged at the under side of the arch for supporting the bricks or units of the arch during the formation of the latter.

45 A further object is the production of apparatus which will be of durable and economical construction and efficient in use.

Other objects will appear hereinafter.

The invention consists in the combinations and arrangements of parts hereinafter described and claimed.

The invention will be best understood by reference to the accompanying drawing forming a part of this specification, and in 55 which—

Figure 1 is a sectional end elevation of an

open hearth furnace the roof of which is in the course of repair through the use of apparatus embodying my invention, Fig. 2 is a perspective view of one of the bricks or units used in the construction of an arch where my apparatus and process is employed, Fig. 3 is a central longitudinal section of the unit or brick, and Fig. 4 is a perspective view of one of the arch unit suspending members included in my invention.

The preferred form of construction as illustrated in the drawing includes the use of a substantially inverted U-shape supporting member 1 the upper side of which is of 70 a curvature corresponding with that of the arch or roof 2 which it is desired to repair or build. The lower extremities of the depending portions of the member 1 are provided with suitable bases 3 which serve to hold said supporting member in upright 75 position during employment.

In the repair of an arch of a roof as shown in Fig. 1, the supporting member 1 is arranged over the opening 4 in the roof which it is desired to repair, the ends of the member 1 being rested upon the roof as shown. The bricks or units 5 which are used to repair the opening or damaged arch are suspended by hook members 6 from the supporting member 1. The suspending members 6 are provided with hooks 7 at their upper ends for engagement over the supporting member 1, the lower ends of said suspension members being provided with 85 hooks 8 for engagement of slots or sockets 9 provided for the reception thereof in the upper ends of the units 5 as clearly shown. After the completion of the arch, the same being then capable of supporting itself, the 90 suspension members 6 may be disengaged from the units 5 and said suspension members together with the supporting member 1 removed. In order to permit of ready disengagement of the hooks 8 from the units 5, 100 as mentioned, the upper ends of said units are so slotted that the hooks 8 may be moved rearwardly to disengagement from the slot 9 notwithstanding that the contiguous face of the adjacent unit closes the outer lateral extremity of said slot.

In order to permit of the suspension members 6 being arranged in position suspended from the member 1, when the furnace is in use, said suspension members are provided with eyes or loops 10 which may be engaged by long hooked rods or other positioning

tools which may be employed by the men in order to permit of the latter standing at a distance from the opening from which hot gases are emitted. A swivel 11 is interposed 5 in each of the suspension members in order to permit of ready adjustment of the bricks in proper relative position when the same are arranged side by side as clearly shown in Fig. 1.

10 It is understood that where the opening in the roof, which is to be repaired, extends over more than one transverse line or arch of bricks, the member 1, after being used in the formation of one arch will be moved along 15 to the next, and so on until the entire opening is repaired. Where it is desired to use the device in completely building an arch, it is understood that the member 1 will be simply increased in length to correspond with 20 the length of the arch which it is desired to build. Or, in the building of an arched roof, if desired, a plurality of supporting members may be used extending longitudinally of the roof, each of said members 1 25 then being used to support the corresponding brick of a number of arches which will be simultaneously formed, it being necessary in this case to employ as many supporting hook members 6 as there are bricks or units 30 in each arch.

While I have illustrated and described the preferred form of construction and process

for carrying my invention into effect, these are capable of variation and modification without departing from the spirit of the invention. I, therefore, do not wish to be limited to the precise details of construction set forth or to the precise steps employed in the process, but desire to avail myself of such variations and modifications as come within 40 the scope of the appended claim.

Having described my invention what I claim as new and desire to secure by Letters Patent is:

In combination with a furnace, of a supporting bar parallel with the top wall of said furnace, foot members loosely resting on said furnace and spacing said bar thereabove; and brick supporting members depending from said supporting bar, each 45 formed of two rods, one bent forming an eye at its lower end and a hook at its upper end and the other having its upper end passed through said eye and a head thereon 50 above such eye, a hook bent on its lower end and its central portion bent forming a loop, substantially as described.

In testimony whereof I have signed my name to this specification in the presence of two subscribing witnesses.

ARTHUR E. SCHUFFENHAUER.
